(57) **CLAIM**

The ornamental design for an ultrasonic skin care device, as shown and described.

DESCRIPTION

FIG. 1 is a perspective view of an ultrasonic skin care device, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof, in closed condition; and,

FIG. 9 is a top view thereof, in open condition, the broken line showing of the jigs being for illustrative purposes only and forming no part of the claimed design.
